United States Patent Office

Des. 186,681
Patented Nov. 17, 1959

186,681

DECANTER OR THE LIKE

Henry R. Fischer, Mount Prospect, Ill., assignor to Cory
Corporation, Chicago, Ill., a corporation of Delaware

Application June 24, 1959, Serial No. 56,524

Term of patent 7 years

(Cl. D44—21)

Fig. 3.

Fig. 4.

Fig. 1 is a side elevation of a decanter or the like showing my new design;

Fig. 2 is a top plan thereof;

Fig. 3 is a front elevation thereof; and

Fig. 4 is a rear elevation thereof.

I claim:

The ornamental design for a decanter or the like, as shown.
